UNITED STATES PATENT OFFICE.

WILLIAM B. HAWTHORNE, OF CHICAGO, ILLINOIS.

DESIGN FOR A RADIATOR CAP.

Application filed December 23, 1925. Serial No. 15,829. Term of patent 14 years.

To all whom it may concern:

Be it known that I, WILLIAM B. HAWTHORNE, a citizen of the United States, and a resident of Chicago, in the county of Cook and State of Illinois, have invented a new, original, and ornamental Design for a Radiator Cap, of which the following is a specification, reference being made to the accompanying drawings, forming a part hereof.

In the drawings:—

Figure 1 is a vertical front elevation of my design for a radiator cap.

Figure 2 is a vertical side elevation thereof.

I claim:—

The ornamental design for a radiator cap, as shown.

WILLIAM B. HAWTHORNE.
